UNITED STATES PATENT OFFICE.

WILBER D. FORSYTH AND ENOS T. BELL, OF PITTSBURG, PENNSYLVANIA.

DESIGN FOR A CUTTER FOR BOILER-TUBE CLEANERS.

SPECIFICATION forming part of Design No. 31,370, dated August 8, 1899.

Application filed July 8, 1899. Serial No. 723,244. Term of patent 14 years.

To all whom it may concern:

Be it known that we, WILBER D. FORSYTH and ENOS T. BELL, citizens of the United States, and residents of Pittsburg, in the county of Allegheny and State of Pennsylvania, have invented a certain new and original Design for a Cutter for Boiler-Tube Cleaners; and we do declare the following to be a full, clear, and exact description of the invention, such as will enable others skilled in the art to which it appertains to make and use the same, reference being had to the accompanying drawings, and to letters of reference marked thereon, which form a part of this specification.

Figure 1 of the drawings is a side elevation of our invention. Fig. 2 is an end elevation of same.

This invention has relation to a certain new and original design for cutters.

The leading feature of the invention consists in a cutter whose body is of slightly-ta-

pered conoidal form and has segmental beveled or wedge-form short ribs or projections spirally disposed thereon and separated from each other by grooves running in spiral lines from one end of the cutter to the other.

In the accompanying drawings the letter A designates the comparatively short tapered conoidal body of the cutter; b, the segmental wedge-form short ribs or projections; C, the intersecting spiral grooves, and d an axial opening through said body.

What we claim is—

The design for a cutter for boiler-tube cleaners, substantially as herein shown and described.

In testimony whereof we affix our signatures in presence of two witnesses.

WILBER D. FORSYTH.
ENOS T. BELL.
